United States Patent Office

Des. 197,395
Patented Jan. 21, 1964

197,395

FOOD COOKING, WARMING, AND VENDING UNIT

Otto E. Werner, Skokie, Ill., assignor to Automatic Canteen Company of America, Chicago, Ill., a corporation of Delaware

Filed Sept. 25, 1961, Ser. No. 66,849

Term of patent 14 years

(Cl. D81—10)

FIG. 1

FIG.2.

FIGURE 1 is a perspective view of a food cooking, warming, and vending unit embodying my new design;

FIGURE 2 is a perspective view showing the opposite sides of FIGURE 1;

FIGURE 3 is an enlarged fragmentary perspective view taken from the upper right of FIGURE 2; and

FIGURE 4 is a fragmentary elevational view taken from the right of FIGURE 2.

I claim:

The ornamental design for food cooking, warming, and vending unit, as shown.
